PNEUMATIC PRESSURE PILOT

Frederick E. Lombard, Jr., Dublin, and Edmund D. Haigler, Hatboro, Pa., assignors to American Machine and Metals, Inc., New York, N. Y., a corporation of Delaware

Application October 8, 1954, Serial No. 32,588

Term of patent 14 years

(Cl. D52—1)

Fig. 1.

Fig. 2.

E. B. S.

Fig. 1 is a perspective view of a pneumatic pressure pilot, showing our new design;

Fig. 2 is a front view; and

Fig. 3 is a perspective view from the left side.

We claim:

The ornamental design for a pneumatic pressure pilot, substantially as shown.
